UNITED STATES PATENT OFFICE

154,348

DESIGN FOR A PITCHER

Earl S. Tupper, Upton, Mass.

Application October 5, 1946, Serial No. 133,775

Term of patent 14 years

(Cl. D44—21)

To all whom it may concern:

Be it known that I, Earl S. Tupper, a citizen of the United States, residing at Upton, in the county of Worcester and State of Massachusetts, have invented a new, original, and ornamental Design for a Pitcher, of which the following is a specification, reference being had to the accompanying drawing, forming part thereof.

Fig. 1 is a perspective view;

Fig. 2 is a view in top plan; and

Fig. 3 is a view in side elevation of a pitcher showing my new design.

I claim:

The ornamental design for a pitcher, as shown.
EARL S. TUPPER.
